(No Model.)

C. B. COTTRELL.

PRINTING PRESS.

No. 314,166.

Patented Mar. 17, 1885.

UNITED STATES PATENT OFFICE.

CALVERT B. COTTRELL, OF STONINGTON, CONNECTICUT.

PRINTING-PRESS.

SPECIFICATION forming part of Letters Patent No. 314,166, dated March 17, 1885.

Application filed October 1, 1883. (No model.)

To all whom it may concern:

Be it known that I, CALVERT B. COTTRELL, a citizen of the United States, and a resident of Stonington, in the county of New London 5 and State of Connecticut, have invented a new and useful Improvement in Printing-Presses, of which the following is a specification, reference being had to the accompanying drawings.

10 My invention relates to the feed-gages which are used in stop-cylinder printing-presses, and which, once for every revolution of the cylinder, have imparted to them a movement which causes them to be projected beyond the periphery of the cylinder and to be withdrawn within the cylinder.

15 The invention consists in the combination, with the impression-cylinder and feed-gages, of novel means, particularly hereinafter described, and pointed out in the claims, whereby the feed-gages are supported and have imparted to them the necessary movements.

20 The invention also consists in the combination, with the impression-cylinder of a stop-cylinder printing-press and tympan-nippers attached thereto, of feed-gages movable inward and outward within and from said cylinder, and a stop-bar attached to said nippers to serve as a stop to said gages, as fully hereinafter described.

25 Figure 1 in the drawings is a side view of the cylinder of a stop-cylinder printing-press and such other parts of the said press as are necessary to illustrate my invention. Fig. 2 is a front view of a part of the cylinder and immediately adjacent parts corresponding with Fig. 1. Fig. 3 is a longitudinal section corresponding with Fig. 2. Fig. 4 is a front view of one of the gages, on a larger scale than 30 Figs. 1, 2, 3. Fig. 5 is a side view corresponding with Fig. 4, but showing also the means of stopping the gages in proper position.

35 A represents a portion of one of the side frames of the press.

40 B is the cylinder, which is intended to be provided with grippers, which, as they may be mounted in the usual manner within the recess *a*, I have not considered it necessary to represent.

45 C is the feed-board.
b is a rock-shaft, on which are mounted the

feed-gages *c*, of which there may be two or more, but of which only one is shown. This shaft is arranged parallel with the axis of the cylinder within the gripper-recess *a*, where it 55 is supported in bearings provided on or attached to the arms of the cylinder. The gages *c* are not attached directly to this rock-shaft *b*, but each is attached to one of the arms *d* of a second rock-shaft, *e*, which is arranged parallel with *b* in bearings in arms *f*, which are affixed to the latter, and of which there should be at least two, one to support each end of said rock-shaft *e*.

50 On the rock-shaft *e* is affixed another arm, *g*, on which is an anti-friction roller, *n*, which is opposite a cam, *h*, affixed to one of the arms of the cylinder, and on the rock-shaft *b* there is affixed outside of the cylinder an arm, *i*, which carries an anti-friction roller, *s*, situated 60 opposite to a cam-lever, *E*, which works on a fixed fulcrum, *j*, secured in a bracket, *F*, attached to the side frame, *A*. The rock-shaft *b* has applied to it a coiled spring, *k*, which tends to turn it in a direction to draw its arms 65 *f* toward the center of the cylinder and so withdraw the feed-gages *c* within the cylinder, as shown in dotted outline in Fig. 1, and the rock-shaft *e* has applied to it a coiled spring, *l*, which tends to turn it in a direction 70 to draw the feed-gages away from the edge *a'* of the gripper-opening *a* of the cylinder; but this spring *l* might be dispensed with by a proper construction of the cam *h*.

75 The operation of projecting the feed-gages beyond the periphery of the cylinder at the proper time for feeding the sheet to the cylinder is produced and controlled by the cam-lever *E*, assisted by the spring *k* or springs *k l*, and the cam *h*. The cam-lever *E* might have 80 the necessary motion for this purpose imparted to it in various ways; but in the example represented the said motion is derived through a rod, *G*, from a cam, *H*, on the side shaft, *I*, which is common to many stop-cylinder 85 presses. The operation takes place after the cylinder has stopped in the usual position to take the sheet, and while it is stationary, and is as follows: The cam-lever *E*, acting upon the arm *i* of the rock-shaft *b*, depresses 90 the said arm, and raises the arms *f*, the rock-shaft *e*, and the gages, and as the gages 95 100

rise from the cylinder the roller *n* of the arm *g* of the rock-shaft *e*, by passing up the cam *h*, is caused to be thrown forward, and the gages are caused to be thrown back toward the edge 5 *a'* of the gripper-opening, all as shown in bold outline in Fig. 1. Immediately after the cylinder starts, the roller *S* passes out of the way of the cam-lever *E*, and the spring *k* turns the rock-shaft *b* in a direction to depress the arms 10 *f* and rock-shaft *e*, and so cause the gages *c* to be withdrawn entirely within the cylinder, so that they will not interfere with the printing, and will permit the edge of the feed-board to be arranged as close as may be desirable to 15 the cylinder. The feed-gages themselves may be of any suitable form and construction that will enable them to properly stop the front edge of the sheet. Those represented consist each of a flat plate, which is fastened to a 20 flange, *d'*, on the upper end of its carrying-arm *d*, and on the upper face of which is a projection made with a lip, *C'*, under which the edge of the sheet passes, and against the portion *C'* of which, below said lip, the sheet 25 is arrested, the upper surface of the plate *C* being brought flush, or nearly so, with the periphery of the cylinder, as shown in bold outline in Fig. 1, when the gage is brought up to its operative position. Provision for adjusting the gages forward or backward on the arms *d* is afforded by providing slots in the gages and securing them to the said arms by screws *m*, passing through said slots and screwing into the said arms. The gages, when 30 brought to a position for receiving the sheet, require to come to a very positive stop, or, in other words, to come to a solid unyielding bearing. In the example represented this

stop consists of a bar, *t*, which is attached firmly to the front of the tympan-nippers *p*, 40 which are attached to the cylinder in the usual manner, and the arms *d* are provided with projections *q*, to come against this stop. This makes a more solid bearing and positive stop than if the gage were to stop against the pack- 45 ing which laps over the edge *a'* of the gripper-opening of the cylinder.

The gages, instead of being arranged to move inward and outward within and from the cylinder with a swinging motion, as described, 50 might be arranged to work in and out rectilinearly under the control of slides or guides.

What I claim as my invention, and desire to secure by Letters Patent, is—

1. The combination, with the cylinder *B*, of 55 the rock-shaft *b*, having arms *f* and *i*, the rock-shaft *e*, supported in said arms *f*, and having arms *d* *g*, the feed-gages attached to said arms *d*, the cam *h*, attached to the cylinder, and mechanism, substantially as herein 60 specified, for producing and controlling the operation of the rock-shaft *b*, for moving the feed-gages within and from the cylinder, substantially as herein set forth.
2. The combination, with the impression- 65 cylinder of a stop-cylinder printing-press and the tympan-nippers attached thereto, of feed-gages movable inward and outward within and from said cylinder, and a stop-bar, *t*, attached to said nippers to serve as a stop to 70 said gages, substantially as herein described.

C. B. COTTRELL.
